(57) **CLAIM**

The ornamental design for a ladder top, as shown and described.

DESCRIPTION

FIG. 1 is a rear perspective view of a ladder top showing our new design;

FIG. 2 is a front perspective view thereof;

FIG. 3 is a top elevational view thereof;

FIG. 4 is a left side elevational view thereof;

FIG. 5 is a right side elevational view thereof;

FIG. 6 is a back side elevational view thereof;

FIG. 7 is a front side elevational view thereof; and,

FIG. 8 is a bottom elevational view thereof.

The broken lines shown in the figures are included for the purpose of illustrating portions of the ladder top and form no part of the claimed design.
